UNITED STATES PATENT OFFICE.

FRANCIS M. KIDDER AND MILTON H. KIDDER, OF NEW YORK, N. Y.

CIRCUIT-INTERRUPTER FOR THERAPEUTICAL APPARATUS.

1,117,857.

Specification of Letters Patent. Patented Nov. 17, 1914.

Application filed January 7, 1914. Serial No. 810,812.

To all whom it may concern:

Be it known that we, FRANCIS M. KIDDER and MILTON H. KIDDER, citizens of the United States, and residents of the city of New York, borough of Manhattan, in the county and State of New York, have invented a new and Improved Circuit-Interrupter for Therapeutic Apparatus, of which the following is a full, clear, and exact description.

This invention relates to circuit interrupters for high frequency apparatus as used for therapeutical treatments, although the invention is not necessarily limited to this use.

The invention has for its general objects to improve and simplify the construction and operation of apparatus of the character referred to so as to be reliable and efficient in use, comparatively inexpensive to manufacture and of such design as to be conveniently handled.

A more specific object of the invention is the provision of novel means for regulating the strength of the treating current by adjusting the armature of the interrupter, there being used in connection with the said adjusting means a device whereby it is impossible to adjust the armature beyond its vibratory limit, or too close to the pole of the interrupter.

With these objects in view, and others which will appear as the description proceeds, the invention comprises various novel features of construction and arrangement of parts such as will be set forth with particularity in the following description and claims appended hereto.

In the accompanying drawing, which illustrates one embodiment of the invention, and wherein similar characters of reference indicate corresponding parts in all the views, Figure 1 is a perspective view of the complete apparatus for generating ultra-violet rays; Fig. 2 is a detail view of parts of the vibrator; Fig. 3 is a diagrammatic view of the circuit connections; Fig. 4 is a side view of a modification showing a stop means for preventing the armature from being adjustable too near to or against the core of the vibrating coil; Fig. 5 is a perspective view of the bracket for supporting the said stop means; Fig. 6 is a perspective view of the pawl of the stop means; Fig. 7 is a perspective view of the armature adjusting screw and ratchet wheel with which the pawl engages.

Referring to the drawing, A designates an evacuated tube or electrode of any desired type which produces ultra-violet rays, the same being removably inserted in one end 60 of the handle B, which has attached thereto a current supply cord C which is provided with a plug D for connection with a suitable supply socket.

Within the handle B are arranged electrical devices shown in the diagram, Fig. 3, which shows the leading in wires 19 and 20 connected respectively with the switch contact 16, and the induction coil winding 6 on the core 5, the other terminal of the winding 6 being connected by a wire 21 with the vibrator spring 11, which is adapted to engage the adjusting screw or contact 13 which is in turn connected by a wire 22 with the primary winding p of the transformer, such primary winding having its opposite terminal connected by the wire 23 with the contact 16^a of the switch. The secondary winding s has one terminal connected with the wire 23 while its opposite 80 terminal is connected with the split sleeve or contact 4 that receives the electrode contact (not shown) on the electrode A. Arranged in shunt relation to the parts 11 and 13 of the vibrator is the condenser 7, one terminal of which is connected by the wire 24 with the wire 21, and the other terminal is connected by a wire 25 with the wire 23. Coacting with the contacts 16, 16^a is a movable contact 17 which is pivotally fastened 90 to the slide 18, Fig. 1, so that, as the device is held in the hand of the operator, it is merely necessary to move the slide 18 back and forth by the thumb to open or close the circuit.

In operation, the current when turned on traverses the magnet windings 6 which energize the magnet core 5 that causes the armature 12 to be attracted away from the contact 13, thereby breaking the primary circuit 100 and causing the magnet to become deenergized, whereby the circuit is again closed through the armature or contact 12 engaging the contact. This making and breaking or energizing and deenergizing of the magnet 105 occurs at frequencies determined by the adjustment of the contact 13, and as a result there is an intermittent charging and discharging of the condenser, which is shunted on the interrupter contacts, so that the high 110 frequency oscillatory currents, characteristic of condenser discharges, are sent through

the primary p , thereby inducing a high frequency and high voltage alternating current in the secondary winding s , whereby ultra-violet rays are caused to be generated in the 5 electrode A in the well-known manner. The primary circuit is readily controlled by the manipulation of the switch on the handle, and by turning the knob 14 of the vibrator screw the intensity of the ultra-violet rays 10 can be varied.

On the heads 1 and 2 of the handle are axially projecting spaced posts 1^c, 2^c which serve as convenient means whereby the cord C can be wound back and forth on the handle from one end to the other in loops forming a figure 8. The posts serve to retain the ends of the loops of the coils on the handle. By this means the whole apparatus takes up comparatively little space and can be conveniently carried in the pocket. 15

There is a liability, in adjusting the vibrator, of screwing the armature down into contact with the core of the vibrating coil, whereby the vibrating function is destroyed 20 and a continuous current will flow through the coil with the possibility of the latter burning out. A safety device is therefore desirable to prevent this abnormal adjustment of the armature, and consequently 25 means for limiting or stopping the effective adjustment of the armature toward the coil core is provided in the nature shown in Figs. 5 to 7 inclusive. Fastened to the core is a bracket 30 which has a pair of arms 31 and 30 32 for supporting a pivoted pawl 33, said pawl having a hub or base portion 34 provided with journals 35 and 36 which engage respectively in a bearing opening 37 in the lug 31 and in a bearing forming screw 38 in 35 the lug 32. The upper end 39 of the pawl is adapted to engage with a ratchet wheel 40 fixed on the armature adjusting screw 14^a. Projecting from the base portion of the pawl is a spring arm 41 which engages under the 40 armature spring 11^a, so that when the armature is moved toward the core of the coil the pawl extremity 39 is thrown into engagement with the ratchet wheel 40, thereby preventing the screw 14^a from being turned any 45 further, and bringing the armature in contact with the coil core. To provide for the proper adjustment of the parts the bracket 30 has a slot 42 for receiving the screw 43 which fastens the bracket in place, and by 50 reason of this slot the bracket can be raised or lowered, thereby bringing the spring arm 41 into proper relation with the armature. To keep the pawl normally away from the ratchet wheel 40, the bracket 30 has a spring 55 44 so arranged that its free end will engage the base of the pawl at the side of the pivotal axis thereof opposite from the extremity 30, and consequently such extremity 39 is held away from the ratchet wheel. 60

65 From the foregoing description taken in

connection with the accompanying drawings, the advantages of the construction and method of operation will be readily understood by those skilled in the art to which the invention appertains, and while we have described the principle of operation, together with the apparatus which we now consider to be the best embodiment thereof, we desire to have it understood that the apparatus shown is merely illustrative, and that such changes may be made when desired as are within the scope of the appended claims. 70

Having thus described our invention, we claim as new and desire to secure by Letters Patent:

1. The combination of an induction coil including a core, an armature movably mounted with respect to the core, a movably mounted member engaged with the armature and movable therewith, means for adjusting the position of the armature, and a stop device movable with the said means and arranged to be engaged by the said member, whereby the latter prevents the armature from being adjusted into contact with the core. 85

2. The combination of a vibrator coil, an armature for the coil, a spring tensioning the armature away from the coil, means adjustable for obtaining the initial position of the armature, and means for preventing the armature from being adjusted by the first-mentioned means to a point beyond the vibratory action of the said spring. 95

3. The combination of a vibrator coil, an armature therefor, means adjustable to vary the position of the armature, and means for limiting the adjustment of the armature toward the coil. 100

4. In an apparatus of the class described, the combination of a coil, an armature attracted thereby, a spring tensioning the armature away from the coil, means for adjusting the initial position of the armature, and a stop device movable with the adjustment of the armature and operative to prevent movement of the said adjusting means beyond a certain point. 105

5. In an apparatus of the class described, the combination of a coil, an armature attracted thereby, a spring tensioning the armature away from the coil, a screw for adjusting the armature toward the coil, a spring-pressed pawl mounted adjacent the armature and having a yielding member operatively connecting the pawl and armature, and an element carried by the screw and with which the pawl engages to prevent further turning of the screw when the armature is at its minimum operative distance 110 115 120 125 from the coil.

6. The combination of a vibrator coil including a core, a movable armature, a pivoted member engaging the armature to be moved thereby in one direction, a spring 130

operating on the member to move it in the opposite direction, a screw for adjusting the position of the armature, a support fixed with respect to the core and in which the 5 screw is threaded, and a member carried by and movable with the screw and arranged to arrest the movement of the first-mentioned member before the armature is adjusted to non-vibratory position.

In testimony whereof we have signed our 10 names to this specification in the presence of two subscribing witnesses.
